Primary Examiner — Freda S Nunn*(74) Attorney, Agent, or Firm* — Lerner, David, Littenberg, Krumholz & Mentlik, LLP**CLAIM**

The ornamental design for a notebook computer housing, as shown and described.

DESCRIPTION

FIG. 1 is a top-rear perspective view of a notebook computer housing shown in a closed configuration according to our design;

FIG. 2 is a top view thereof;

FIG. 3 is a bottom view thereof;

FIG. 4 is a front side view thereof;

FIG. 5 is a back side view thereof;

FIG. 6 is a right side view thereof;

FIG. 7 is a left side view thereof;

FIG. 8 is a top-front perspective view thereof in an open configuration;

FIG. 9 is a top view thereof;

FIG. 10 is a bottom view thereof;

FIG. 11 is a front side view thereof;

FIG. 12 is a back side view thereof;

FIG. 13 is a right side view thereof; and,

FIG. 14 is a left side view thereof.

The broken lines shown in FIGS. 3, 8, 9, 10 and 11 that are immediately adjacent to the shaded areas represent the bounds of the claimed design, while all other lines are directed to environment and form no part of the claimed design.
